P. J. CUNNINGHAM.

DOOR LATCH

APPLICATION FILED OCT. 24, 1917.

1,265,886.

Patented May 14, 1918.

Inventor

PETER J. CUNNINGHAM.

By *Watson E. Coleman*

Attorney

UNITED STATES PATENT OFFICE.

PETER J. CUNNINGHAM, OF JARBIDGE, NEVADA.

DOOR-LATCH.

1,265,886.

Specification of Letters Patent. Patented May 14, 1918.

Application filed October 24, 1917. Serial No. 198,238.

To all whom it may concern:

Be it known that I, PETER J. CUNNINGHAM, a citizen of the United States, residing at Jarbidge, in the county of Elko and State 5 of Nevada, have invented certain new and useful Improvements in Door-Latches, of which the following is a specification, reference being had to the accompanying drawings.

10 This invention relates to an improved door latch and has for its primary object to provide simple, effective, and inexpensive means for securely latching screen doors and the like to hold the same tightly closed at the 15 top of the door, as well as the bottom thereof.

It is another and more particular object of the invention to provide a knob actuated door latch embodying latch bolts movable in the door at right angles with respect to each 20 other, a flexible connection between one of said bolts and the knob rod to retract said bolt when the rod is turned in one direction, means on the other bolt with which the rod co-acts to move the same to its effective and 25 ineffective positions, and a spring acting to project the first named bolt to its locking position.

It is also a further general object of the invention to provide a latch of the above 30 character which may be inexpensively manufactured and applied to the door, is not liable to get out of order, and is positive and reliable in its operation.

With the above and other objects in view, 35 my invention consists in the novel features of construction, combination, and arrangement of parts to be hereinafter more fully described, claimed, and illustrated in the accompanying drawing, in which,

40 Figure 1 is a vertical sectional view through one side of a screen door showing the same latched in its closed position by means of the present invention;

Fig. 2 is a section taken on the line 2—2 of 45 Fig. 1;

Fig. 3 is a section taken on the line 3—3 of Fig. 1; and

Fig. 4 is a detail perspective view of one 50 of the latch bolts.

55 Referring in detail to the drawing, 5 designates a door which is hinged along one of its longitudinal edges upon the door frame in the usual manner, as indicated at 6. In the illustrated embodiment of my invention, I have shown the same applied to a screen door, but it is manifest, of course,

that the device can be used as well upon other door constructions.

Adjacent the free vertical edge of the door and substantially midway between its upper 60 and lower ends, said door is provided with a transverse opening 7 in which the female section 8 of a knob rod snugly fits for rotative movement. This rod section is provided with a longitudinal, rectangular bore 65 9 to receive the rectangular male section 10 of the rod, said rod section having a knob or head 11 on one end which may be of any preferred ornamental form. The rod section 8 is also provided with an enlarged, tapering, end portion having an ornamental head 12. A metal plate 13 is engaged over the face of said head and a screw 14 is disposed through a central aperture in said plate and threaded in the end of the rod section 10, whereby said rod sections are held, 70 in assembled relation for turning movement as a unit.

In the central portion of the door, a rectangular opening 13 is provided, in which 80 the horizontally movable latch bolt 14' is disposed. This opening 13 is intersected by the transverse opening 7 in the door, and the end of the rod section 8 fitting within said opening has its lower portion cut away, as 85 shown at 15. Spaced, upstanding pins 16 fixed in the latch bolt 14', extend into this cut-away portion of the rod section. A rod or pin 17 also projects longitudinally from the end of the rod section 8 and extends between the spaced pins 16. It will thus be 90 apparent that when the knob rod is rotated in one direction, the pin 17 co-acting with one of the pins 16 will draw the latch bolt 14 inwardly, releasing said bolt from engagement with the keeper 18 fixed in the door frame. A stop pin 19 is fixed in the door and projects into the opening 7, said pin limiting the reverse rotation of the knob rod by the engagement of the pin 17 therewith. 100

In conjunction with the horizontally movable latch bolt 14', I also provide a vertically movable latch bolt 20 which is mounted for movement in the upper end of a longitudinally extending opening 21 formed in 105 the door, said opening communicating at its lower end with the transverse opening 7. The wall of this opening, in spaced relation to its upper end, is provided with a shoulder indicated at 22, against which one end of a 110 coil spring 23 is seated, the other end of said spring acting against the latch bolt 20

to project the same upwardly above the upper edge of the door. A chain or other flexible element 24 extends through the opening 21 and has its upper end suitably attached to the bolt 20, the lower end of said chain extending around a peripheral groove 25 formed in the knob rod section 8 and being connected to the pin 19. It will thus be apparent that when the knob rod is rotated to 10 release the latch bolt 14', there will also be a downward pull upon the chain 24 so that the latch bolt 20 will be drawn downwardly against the action of the spring 23 and disengaged from the keeper indicated at 26, which is fixed in the top bar of the door frame.

From the foregoing description, taken in connection with the accompanying drawing, it is believed that the construction and several advantages of the invention will be 20 clearly and fully understood. When the knob is turned in the proper direction, the two latch bolts 14' and 20 will be simultaneously retracted so that the door may be swung to its open position, and when the 25 knob is released, the spring 23 acts to again project the latch bolts beyond the edges of the door so that when the door is closed, they will properly engage in the keepers. By providing the latch bolt at the top of 30 the door, the door will be held securely closed within the frame and warping of the door prevented. The device is thus well adapted for use upon heavy storm doors and, if desired, an additional latch bolt 35 may be used at the bottom of the door and connected to the knob rod section 8 in the same manner as above explained, so that all three bolts would be simultaneously operated. It will further be apparent that the 40 central, horizontally movable latch bolt can be dispensed with if desired. The very simple form and construction of the several parts of my invention enable the same to be manufactured at comparatively small cost 45 and embodied in the door structure without materially increasing the expense thereof.

While I have herein shown and described the preferred form, construction, and arrangement of the various elements, it is to 50 be understood that the device is susceptible of considerable modification and I, therefore, reserve the privilege of adopting all such legitimate changes as may be fairly

embodied within the spirit and scope of the invention as claimed.

55

Having thus fully described my invention, what I desire to claim and secure by Letters Patent is:

1. The combination with a door, sliding latch bolts mounted in the door and movable at right angles to each other, an operating member rotatably mounted in the door, an operating connection between one of said latch bolts and said member, the other of the latch bolts having an operating movement in a plane at right angles to the axis of said member and having one of its ends normally intersecting the plane of said member, an element carried by the operating member and disposed in parallel relation to its axis, means on said latch bolt with which said element coacts whereby the latch bolt is retracted simultaneously with the retraction of the other of the latch bolts in the rotation of the operating member in 70 one direction, and means for projecting the latch bolts to their normal positions.

2. The combination with a door having a transverse opening therein adjacent its free vertical edge and a latch bolt mortise intersected by said opening, of a horizontally movable latch bolt in said mortise, a rod rotatable in said transverse opening, said latch bolt having spaced pins fixed therein projecting into the transverse opening, 80 means on the rod disposed between said pins and co-acting therewith to move said latch bolt, a second latch bolt vertically movable in the door at its upper end, a flexible connection between the latter latch bolt and said rod, whereby the bolts will be simultaneously retracted upon the turning of said rod in one direction, a coil spring co-acting 85 with the latter latch bolt to project the same to its normal position and reverse the turning 90 movement of said rod, and a stop member to be engaged by the latch bolt actuating means on said rod and limit such reverse turning movement of the rod.

In testimony whereof I hereunto affix my 100 signature in the presence of two witnesses.

PETER J. CUNNINGHAM.

Witnesses:

JOE SCHMITT.
